CLARENCE C. STIRLING, OF HARTFORD, CONNECTICUT, ASSIGNOR TO THE HART & HEGERMAN MANUFACTURING COMPANY, OF HARTFORD, CONNECTICUT, A CORPORATION OF CONNECTICUT.

ELECTRIC SWITCH.

1,314,098.

Specification of Letters Patent. Patented Aug. 26, 1919.

Application filed August 14, 1918. Serial No. 249,759.

To all whom it may concern:

Be it known that I, CLARENCE C. STIRLING, a citizen of the United States, residing at Hartford, in the county of Hartford and

5 State of Connecticut, have invented certain new and useful Improvements in Electric Switches, of which the following is a specification.

This invention relates to electric switches.

10 The features of the invention may be embodied in switches of different types, for instance one of the pendent snap kind. I have several motives in view, among them being the provision of an appurtenance of the 15 character set forth, which is quite compact and the action of the parts of which is certain and positive.

In the drawings accompanying and forming part of the present specification I have 20 represented in detail one of the several forms of embodiment of the invention which to enable those skilled in the art to practice the same will be set forth fully in the following description. I do not necessarily 25 restrict myself to this particular disclosure; I may depart therefrom in several respects within the scope of the invention defined by the claims following said description.

Referring to said drawings:

30 Figure 1 is a vertical section of a switch involving the invention.

Fig. 2 is a similar view, the section being taken on the line 2—2 of Fig. 1.

Figs. 3 and 4 are cross sections on the lines 35 3—3 and 4—4 respectively of Fig. 1, looking in the direction of the arrows.

Like characters refer to like parts throughout the several views.

The different parts of the switch may be 40 sustained by a suitable support, that shown for the purpose being denoted by 2. The support comprises in its make-up a cylindrical body 3, practically closed at its upper end and open at the bottom to snugly receive 45 the plug or closing member 4, the plug and top of the body being separated to produce a chamber or cavity in which certain of the operative parts are housed. The body and the plug together with the cap 5 associated 50 therewith are of insulating material, such as common in pendent switches of various kinds. The cap is removably associated with the body for instance by interengaging screw threads. The cap as shown has in its

top the opening 6 through which the complementary wires as 7 are shown as extending, the lower ends of these wires being obviously bared for electrical connection with suitable contact members. The contact members for this purpose are each denoted 55 in a general way by 8. Each involves a body or shank 9 of arcuate formation to fit snugly against the inner surface of the segmental slot or opening 8' in the top of the body 3. Through these bodies 9 are passed 60 the shanks of the holding down screws 10, having a threaded connection with the body 3 diametrically opposite each other, the heads of the screws receiving the bared ends 65 of the two wires 7 and pressing the same 70 against the shanks or bodies 9 of the respective contact members. These shanks or bodies 9 also receive the screws 11 passed through the body 3 from the exterior thereof. The slot or opening 8' is segmental, 75 the result being that what might be considered at one side of said slot or opening is a segmental extension 12 having a notch 13, the function of which will be herein-after explained. One end of each contact 80 member 8 abuts against this segmental extension 12 practically at the base thereof, the other end having an inturned finger or contact portion as 14, the free ends of which diverge slightly inwardly so as to properly 85 receive between them the coöperating switch member or contactor. Obviously the contact fingers or portions 14 possess a certain amount of resiliency.

The switching member or contact is denoted in a general way by 15. It comprises two sides or complementary branches 16 practically in parallelism with each other and united at their upper ends by the connecting piece or cylinder 17. Between these branches 95 16 extends the push-rod 18 constituting a suitable actuator for the switching member or contactor. These arms, branches or sides 16 of the switching member are springy or resilient, and the reason for this will herein-after appear and may be made of suitable material such as spring stock. The connecting piece or cylinder 17 acts in connection with the upper ends of the complementary branches of the switching member to bridge 100 105 across the contact members 8 when the circuit is closed as shown for instance by dotted lines in Fig. 1. When the switching mem-

ber is in this relation, obviously it carries the current across the two contact members. The push-rod extends comparatively freely through diametrically opposite openings 19

5 in the cylindrical part of the body 3 and its ends are manipulable to effect the action of the switch to either open or close the circuit as shown respectively by full and dotted lines in said Fig. 1.

10 The branches or sides 16 have inturned feet 20 which as shown are at all times in overlapped relation, these feet having respectively angular faces 21 and 22 which converge at the outer ends of the respective feet practically centrally thereof. Through the branches or sides 16 of the switching member and also through the actuator or push-rod 18 substantially centrally of the length thereof extends freely 15 the pin 23, the ends of the pin entering quite freely diametrically opposite elongated slots or notches 24 in the cylindrical part of the body 3. Rising from the bottom 4 practically centrally thereof is the stud or projection 25 constituting a suitable governing element.

In Fig. 1 the full lines show the parts in the open-circuited position. At this time the fixed or stationary stud 25 fits a mouth or aperture in the switching member 15 jointly produced by the similar faces 21 as shown for example by full lines in Fig. 4. It will be supposed that it is desired to close the circuit. In this event the following procedure will be adopted: The push-rod 18 will be thrust to the left in said Fig. 1 and will carry the lower portion of the switching member 15 therewith, the stud on said motion entering the space presented jointly by the two faces 21 and thus expand outwardly the lower portions of the resilient or spring branches 16, the motion continuing until the apexes or juncture of the faces 21 and 22 of said branches reach the transverse center line of the fixed stud 25. They are almost shown in this particular relation by the two series of dotted lines on the right in Fig. 4, the push-rod during this time being assumed to be moving in the direction 45 of the arrow. In this particular view the said apexes have not quite reached the transverse center line of the stud. When, however, they have passed said transverse center line, the branches or sides 16 by their 50 resiliency approach each other and the faces 22 relatively ride down the stud 25 at an accelerated rate of speed and at the same time cause the snap movement of the switching member on or about the pivot or pin 22 55 and the consequent projection of the principal part of the switching member between the fingers or contact portions 14. When the parts are shown in the off relation as shown by full lines in said Fig. 1 and best in Fig. 60 65 3, the upper portion of the switching mem-

ber 15 it will be perceived, fits within the notch 13, which is diametrically opposite to the space between the fingers or contact portions 14.

What I claim is:

1. An electric switch comprising an actuator, a swinging switching member including a spring arm which swings therewith, the actuator being connected with the switching member, and a fixed stud supported independently of the actuator and the switching member, in the path of movement of the spring arm, the actuator on its movement causing the spring arm to traverse the stud and thus bend the same in a direction transverse to the direction of swinging motion of the switching member and thereby condition the spring arm for imparting a snap movement to the switching member when the spring arm is released by 80 the stud, the actuator having a movement beyond the point at which the spring arm is thus conditioned, during which the stud releases the spring arm.

2. An electric switch comprising an actuator, a swinging switching member including spaced spring arms which swing therewith, the actuator being connected with the switching member, and a stud supported independently of the actuator and the switching member, in the path of the spring arms, the actuator on its movement causing the spring arms to traverse opposite sides of the stud and the stud thereby bending the spring arms simultaneously in a direction transverse to the direction of swinging motion of the switching member to thereby condition the spring arms to impart a snap movement to the switching member when released, the actuator having a movement beyond which the said spring arms are thus bent to release the arms, and the arms when freed imparting a snap movement to the switching member.

3. An electric switch comprising an actuator, a swinging switching member including a spring arm which swings therewith, the actuator being connected with the switching member, and a fixed cylindrical stud supported independently of the actuator and the switching member, in the path of movement of the spring arm, the actuator on its movement causing the spring arm to traverse the stud and thus bend the arm in a direction transverse to the direction of swinging movement of the switching member and thereby condition the spring arm to impart a snap movement to the switching member when the spring arm is released by the stud, the actuator having a movement beyond the point at which the spring arm is thus conditioned during which the stud releases the spring arm, the latter acting to complete the motion of the switching member.

4. An electric switch including an actu-

ator, mounted for back and forth movements in a straight path, a swinging switching member including spaced spring arms which swing therewith, the spring arms being located at opposite sides of the actuator and being operatively connected therewith between the ends thereof, and a stud supported independently of the actuator and the switching member, in the path of the spring arms, the actuator on its movement causing the spring arms to traverse opposite sides of the stud, the latter thereby bending the spring arms simultaneously in a direction transverse to the direction of swinging motion of the switching member to thereby condition the spring arms to impart a snap movement to the switching member when released, the actuator having a movement beyond that during which said spring arms are thus bent to release the arms and the arms when freed imparting a snap movement to the switching member.

5. An electric switch comprising an actuator, a bodily movable switching member having resilient arms, the actuator being connected with the switching member, and a fixed stud, the actuator being adapted to cause the spring arms to engage the stud and thus spread the arms and subsequently free the same from the stud, the arms when freed acting to cause a snap movement of the switching member.

6. An electric switch comprising an actuator, a bodily movable swinging switching member having spring arms, an actuator extending between the spring arms, a pin extending through the spring arms and also through the actuator and mounted for lateral movement, and a fixed stud, the actuator being adapted to cause the spring arms to ride along and then pass free of the stud, the spring arms as they ride along the stud being conditioned to impart a snap movement to the switching member and causing said movement when they are freed.

7. An electric switch comprising an actuator, a bodily movable swinging switching member having resilient side branches, the actuator being connected with the switching member, and an abutment supported independently of the actuator and the switching member, the actuator on its movement causing the switching member to traverse the abutment and at the same time flex the branches thereof in condition to cause the same to impart a snap movement to the switching member, the actuator having a continued movement beyond the point at which the said branches are thus tensioned during which the abutment releases the switching member and the branches when the switching member is thus released imparting a snap movement to the switching member.

8. An electric switch comprising an actu-

ator, a swinging resilient switching member connected with the actuator for swinging movement thereby, and means for causing the flexing of the switching member to thus tension the same and then its release, whereby it can react, the tensioning movement being transverse to the swinging movement.

9. An electric switch comprising an actuator and a swinging switching member having resilient side branches jointed to the actuator, and means for causing the separation of the branches of the switching member on a predetermined movement of the actuator and then releasing said branches, so that they can resume their initial positions and thus cause a snap movement of the switching member.

10. An electric switch comprising an actuator, a switching member including spring means, the actuator being connected with the switching member, and a stud supported independently of the actuator and the switching member, the actuator on its movement causing the spring means to traverse the stud in a direction transverse to the switching movement of the switching member, and thereby bend the spring means in a direction transverse to the operative motion of the switching member for imparting a snap movement to the switching member, when the spring means is freed by said stud.

11. An electric switch comprising an actuator, a bodily movable switching member having resilient side branches, the actuator being connected with the switching member and the said branches having in turn overlapping feet provided with faces which converge at the outer ends of the feet practically centrally thereof, and a fixed stud, the actuator being adapted to cause said faces to engage the stud and thus separate said side branches, and subsequently to free the same from the stud, the branches when freed reacting to cause a snap movement of the switching member.

12. An electric switch comprising an actuator, a bodily movable switching member having resilient side branches, the actuator being connected with the switching member and the said branches having in turn overlapping feet provided with faces which converge at the outer ends of the feet, and a fixed stud, the actuator being adapted to cause said faces to engage the stud and thus separate said side branches and subsequently to free the same from the stud, the branches when freed reacting to cause a snap movement of the switching member.

13. An electric switch comprising an actuator, a swinging switching member having resilient side branches, the actuator extending between the branches of the switching member and being connected therewith, said branches having in turn overlapping feet provided with faces, and a fixed stud, the

actuator being adapted to cause the faces to engage the stud and thus separate said side branches and subsequently to free the same from the stud, the branches when freed reacting to cause a snap movement of the switching member.

14. An electric switch comprising an actuator, a bodily movable switching member having resilient side branches, actuator being extended between and connected with the side branches, the latter having overlapping feet provided with angular faces which converge at the outer ends of the feet practically centrally thereof, and a fixed 10 stud, the actuator being adapted to cause said faces to engage the stud and thus separate said side branches and subsequently to free the same from the stud, the branches when freed reacting to cause a snap movement of the 15 switching member.

15. An electric switch comprising an actu-

ator, a bodily movable swinging member having resilient side branches, an actuator extending between the side branches, a pin extending through the side branches and 25 also through the actuator and mounted for lateral movement, the branches having overlapping feet provided with angular faces which converge at the outer ends of the feet practically centrally thereof, and a fixed 30 stud, the actuator being adapted to cause said faces to engage the stud and thus separate said side branches and subsequently to free the same from the stud, the branches when freed reacting to cause a snap movement of the 35 switching member.

In testimony whereof I affix my signature in the presence of two witnesses.

CLARENCE C. STIRLING.
